UNITED STATES PATENT OFFICE.

GEORGE A. KIRKBRIDE, OF PHILADELPHIA, PENNSYLVANIA.

WORK CLAMP AND GAUGE.

Application filed December 11, 1922. Serial No. 806,138.

To all whom it may concern:

Be it known that I, GEORGE A. KIRKBRIDE, a citizen of the United States, and resident of Philadelphia, in the county of Philadelphia and State of Pennsylvania, have invented certain new and useful Improvements in Work Clamps and Gauges, of which the following is a full, clear, and exact description.

- 10 My invention relates to a clamp and gauge to be used in connection with sewing and perforating machines for forming imitation tips for shoes and other articles where stitching is to be done on a regular curve.
- 15 An object of the invention is to provide such a device with a pivoted clamp which extends to a point adjacent the needles, whereby the article, after being started through the machine, will be guided through the proper curve by means of the clamp and pivot, thereby promoting accuracy and relieving the eyes of the operator.

Another object of the invention is the provision of a device of the above character which is readily adjustable toward or from the needles in order to vary the degree of curvature of the stitching on the tip.

A further object of the invention resides in the use of a gauge in connection with the work clamp, in order that the article to be perforated and stitched will always be accurately positioned so that the line of stitching will be symmetrically arranged thereon.

Another object of the invention is the provision of a gauge which is radially adjustable in order that the length of the imitation tip may be varied.

Other objects and advantages of the invention will be apparent from the following description when taken in connection with the accompanying drawings, in which:

Figure 1 is a fragmentary perspective view of a machine with my attachment in place.

Figure 2 is a fragmentary plan view of the work plate with the clamp and gauge plate attached.

Figure 3 is a section taken on the irregular line 3—3 of Figure 2.

Figure 4 is a section taken on the irregular line 4—4 of Figure 2, and

Figure 5 is a perspective view of the upper member of the work clamp.

Referring to the drawings more in detail,

the numeral 1 indicates the work plate of a sewing machine provided with the usual needle bars 2, presser foot 3 and feeding mechanism 4. Pivoted to the work plate 1 by means of the screw 5 is a radius plate 6. This plate is formed with an arcuate slot 7 and set-screw 8, by means of which its opposite end may be moved toward or from the line of stitching.

Pivoted on the end of the radius plate 6 by means of pin 9 is a work clamp, which comprises the substantially sector-shaped plate 10 and clamping member 11 pivoted thereto, as indicated at 12. A coil spring 13 is provided for normally holding the end of the clamping member 11 in engagement with the plate 10.

By the construction thus far described it is obvious that the work clamp may be adjusted relatively to the line of stitching by loosening the set-screw 8 and swinging the radius plate 6 about its pivot 5. The screw 8 is then tightened and the new pivot point of the work clamp thereby fixed. In this manner the degree of curvature of the line of stitching may be changed at will.

In order that the shoe vamp A may be quickly placed in the clamp in proper position, I have provided the gauge plate 14 having the laterally extending arm 15, which is provided with the diagonal slots 16 and 17. These slots receive the pivot screws 5 and 9 of the radius plate and permit a radial adjustment of the plate in order that the length of the imitation tip may be varied when desired.

It should be here noted that the screw 9 is formed with a shoulder which will engage and lock the gauge plate 14 in position, but will permit a free swinging movement of the work plate. An arcuate slot or line 18 is formed on the gauge plate to be used in positioning the vamps.

In operation, the work clamp is drawn toward the operator and opened and the end of the vamp inserted therein, the usual notches in the side edges of the vamp registering with the gauge line 18. The vamp is then moved under the needles and the operation of forming the imitation tip is automatically completed through the instrumentalities of the feeding mechanism 4 and the pivoted work clamp.

Should it be desired to alter the length of the tips being formed it is only necessary to loosen the set-screws 5 and 9 and move the gauge plate 14 in the proper direction through the medium of the slots 16 and 17.

Also when a different degree of curvature is required for the line of stitching the set-screw 8 may be loosened and the radius plate 6 swung on its pivot until the pivot pin 10 reaches the position desired.

From the foregoing description it will be seen that I have provided an extremely simple mechanism for guiding the work through the stitching machine which not only permits a ready and accurate positioning of the vamp within the work clamp, but also one by which both the length of the tip and its curvature may be varied as desired.

In accordance with the patent statutes I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. In a device of the class described, a radius plate having a slot therein, means for pivoting said radius plate to the work plate

of a sewing machine, a set-screw extending through the slot of the radius plate and adapted to lock the radius plate in adjusted position, and a work clamp pivoted to said radius plate.

2. In a sewing machine having a work plate, a work clamp pivoted to the work plate, and a substantially sector-shaped gauge plate adjustably connected to the work plate between the latter and the work clamp.

3. In a sewing machine having a work plate, a work clamp pivoted to the work plate, means permitting a bodily adjustment of the work clamp toward or from the line of stitching, whereby the degree of curvature of the line of stitching may be varied, and a gauge for co-operation with said work clamp.

4. In a sewing machine having a work plate, a gauge plate mounted thereon, and a work clamp above said gauge plate and pivoted to the work plate, said gauge plate being provided with an arcuate guide line.

5. In a sewing machine having a work plate, a radius plate pivoted to the work plate, means for locking the radius plate in adjusted position, a gauge plate adjustably mounted on the radius plate, a work clamp mounted above said gauge plate, and means for pivoting the work clamp to the radius plate.

GEORGE A. KIRKBRIDE.
